UNITED STATES PATENT OFFICE

2,147,526

AMUSEMENT APPARATUS

Jesse Wilson Farmer, Elm City, N. C.

Application April 19, 1937, Serial No. 137,875

1 Claim. (Cl. 273—118)

This invention appertains to new and useful improvements in amusement apparatus and more particularly to a game of the surface projectile type.

5 The principal object of the present invention is to provide a game which combines certain characteristics of the well known pin and ball games with pool.

10 Another important object of the invention is to provide a game apparatus which combines a skill of game with certain obstacles which will have a tendency to remove the element of luck from the results to be gained.

15 Other important objects and advantages of the invention will become apparent to the reader of the following specification.

In the drawings:—

Figure 1 represents a top plan view of the apparatus.

20 Figure 2 represents a longitudinal sectional view through the apparatus.

Figure 3 is a transverse sectional view on the line 3—3 of Figure 1.

25 Figure 4 is a perspective view of one of the pins.

Figure 5 is an elevational view of one of the balls.

Figure 6 is a perspective view of the cue.

Referring to the drawings wherein like numerals 30 designate like parts, it can be seen that numeral 5 represents the game board having the upstanding side walls 6—6 and the end walls 7—8. Numeral 9 represents a transversely extending partition connecting the side walls 6—6 and being substantially spaced from the end wall 1, dividing the game board into the "play from" area *a* and the "play to" area *b*. The "play from" area is marked off with transverse starting lines 10—11 from which the ball 12 can be shot, while 40 in the area *b* are the plurality of cup-formed peg arrangements 13 and the free pins 14. The surface of the area *b* is marked off with scores 15 adjacent both the pocket 13 and the pin 14.

The partition 9 is provided with a plurality of round openings 16 through which the ball 12 can barely pass.

This game is played by placing one ball on the line 11 of the table and playing another on the line 10. A cue is used to shoot the first ball against the second ball. The object is to get as many balls through the holes of the partition as possible and into the pockets 13, and also by knocking down the pins 14 placed between the 10 pockets. In knocking down a pin the player can set it up and try knocking it down again, but when balls go into the pocket they cannot be played over. Two players can play this game. The winner has the most points counting the 15 numbers of the pockets and pins which he has knocked down.

Various other games can be made up and played with the equipment above set forth.

While the foregoing specification sets forth the 20 invention in specific terms, it is to be understood that numerous changes in the shape, size and materials may be resorted to without departing from the spirit and scope of the invention as claimed hereinafter.

25 Having described the invention what is claimed as new is:—

A game apparatus comprising a board having a side wall and an end wall, a partition connecting the side wall in spaced relation to the end wall 30 and having a plurality of openings therein extending upwardly from the surface of the board, said side walls, end wall and partition defining a "play to" area, and obstacles on the "play to" area adapted to be struck by a surface projectile 35 shot through one of the said openings of the partition, said board being inclined, said objects consisting of pockets formed by pegs driven into the said area and having one side open and facing downwardly with respect to the inclination of the 40 board.

JESSE WILSON FARMER.
